UNITED STATES PATENT OFFICE

ISSIDORE WOSK, OF NEW YORK, N. Y.

LIFE SAVING APPLIANCE

Application filed February 20, 1931. Serial No. 517,336.

This invention relates to life preservers and more particularly to a life saving appliance in the nature of a jacket having inflatable portions, so constructed as to maintain the wearer in a substantially vertical position when in the water.

The primary object of the invention is to provide a simple and efficient life saving jacket including air inflated members so ar-

10 ranged that the center of buoyancy is at a point sufficiently above the center of gravity of the body so that the lower part of the body and the legs will act as a depending weight to hold the head upright above the water.

15 Another object of the invention is to construct a life saving jacket including a plurality of air inflated members to be disposed about the body and so arranged that the jacket will be adjustable to the size of the 20 person's body, so that the appliance may be furnished in standard sizes and conveniently availed of by persons of different bodily size and proportions.

Still another object of the invention is to 25 provide a life saving jacket which may be quickly applied to the person, which will be enabled to cushion the impact of the wearer's body when striking the water as when falling or jumping from a height, and which will 30 tend to maintain the wearer's head in a substantially upright position in case the wearer should become unconscious or injured.

Yet another object of the invention is to 35 construct an adjustable life saving jacket which may be employed in either of several forms, that is to say with air inflated portions disposed about the body only, with air inflated sleeve portions attached to the jacket, and with or without a neck encircling unit 40 also secured to the jacket, either the neck encircling member, or the sleeve portions, or both, being omitted from the body portion if desired.

45 Other objects and advantages of the invention will be hereinafter specifically pointed out, or will become apparent, as the specification proceeds.

50 With the above indicated objects in view, the invention resides in certain novel constructions and combinations and arrangement

of parts, clearly described in the following specification and fully illustrated in the accompanying drawings, which latter show embodiments of the invention as at present preferred.

55

In said drawings:

Fig. 1 is a front elevation showing the complete life saving garment in use;

Fig. 2 is a side view of the arrangement shown in Fig. 1;

Fig. 3 is a plan view showing the inside of the garment, the garment sections being separated at the shoulder seams and spread out for purposes of clarity;

Fig. 4 is a top plan view showing the neck 65 encircling unit;

Figs. 5 and 6 are views similar to Fig. 4 showing the sleeve members;

Fig. 7 is a transverse sectional view through the body portion of the garment, taken substantially on the line 7—7 of Fig. 3;

Fig. 8 is a vertical sectional view through one of the air inflated body portions of the jacket, taken on the line 8—8 of Fig. 3;

Fig. 9 is a front view showing a modification in which the sleeve members shown in Figs. 1 and 2 are omitted; and

Fig. 10 is a view similar to Fig. 9 showing still another modification in which the neck encircling unit is dispensed with.

Referring more particularly to the drawings the life saving jacket 10 in this instance includes a body encircling portion having a pair of back sections 11 and 12, suitably stitched together along a vertical seam as 85 indicated at 13, and a pair of front side sections 14 and 15 suitably stitched together along short vertical seams 16 and 17, or, if desired, constructed in one piece with the back sections 11 and 12 respectively.

90 The body portions or sections 11, 12, 14 and 15 may be constructed of any suitable material, such for instance as relatively light but tough fabric, the garment sections being cut to provide arm holes 18 and 19, and the front portions 14 and 15 having shoulder portions 20 and 21 which are suitably stitched to corresponding shoulder portions 22 and 23 provided on the back sections 11 and 12 respectively.

100

The interior of each of the back sections 11 and 12 is provided with a scalloped or reniform hollow inflatable member 24 and 25 respectively. These inflatable members 24 and 25 are so positioned that the longer and thinner end portions are disposed adjacent to each other, while the portions of greater diameter, when inflated are disposed in substantially the horizontal plane of the body of 10 the wearer. The front sections 14 and 15 are provided with similar air inflatable members 26 and 27 which are reversely arranged, so that when the garment is positioned on the body, the sections 26 and 27 will bear the 15 same relation to each other as the sections 24 and 25 do to each other at the rear of the garment. The air inflatable members 24, 25, 26 and 27 are preferably constructed of rubber and are secured to the body portions 11, 20 12, 14 and 15 of the jacket in any suitable manner, as by sewing the air inflatable members within pockets, or by securely cementing the air inflatable members to the jacket sections; or, the entire body portion may be 25 constructed in one piece with the air inflatable members. Each of the air inflatable members is provided with a suitable air inlet and outlet valve 28 preferably constructed to permit quick filling of the inflatable members and arranged to tightly seal the same 30 so that no unexpected leakage of air can normally occur.

To secure the garment about the body I provide in this instance a plurality of vertically arranged strap members, including a strap 29 at the center line of the back of the garment, straps 30 and 31 extending downward beneath the arm holes 18 and 19, and strap members 32 and 33 disposed at the front 40 of the garment. Each of the strap members 29, 30, 31, 32, and 33 is provided with a loop 34 at its lower end, and a horizontal strap 35 is passed through the aligned loops of the vertical straps. The vertical straps are 45 secured to the body portions of the jacket in any suitable manner, as for instance by stitching the same thereto. The front sections 14 and 15 are provided with two pairs of complementary strap fastening devices 36 and 37 50 respectively and 38 and 39 respectively.

In positioning the garment upon the body the straps 36, 37 and 38, 39 are secured together by means of suitable buckles 40 and 41, and the strap 35 is secured about the waist 55 of the wearer by means of a suitable buckle 42. The garment is thus suitable for use by both thin and stout persons, as well as by tall and short persons. In any case where the strap 35 depends below the waist of the 60 wearer, the strap 35 is simply folded up upon the straps 32, 30, 29, 31 and 33, to shorten the length of the vertical straps, thereby bringing the strap 35 to the wearer's waist line.

65 The garment constructed as described, and

as shown without the appurtenances herein-after referred to, is seen in Fig. 10, and is suitable for ordinary purposes. The garment will maintain the wearer's body in a substantially vertical position, due to the buoyant effect produced by the air inflatable members constructed as shown herein, this construction tending to maintain the center of buoyancy of the person's body at a point above the body's center of gravity, the weight of the 70 lower part of the body tending to hold the wearer's head upright above the water. 75

For use by persons precipitated into the ocean, or other rough water, particularly where the person is likely to remain in the water for a considerable period so as, possibly, to become unconscious, or in cases where the person may be injured, additional means are desirably provided to support the head and insure its being maintained above the 80 surface of the water. For this purpose, in the present instance, I provide upon the body portion of the garment, an air inflatable collar member 43, of substantially U-shaped tubular form. This collar member is desirably formed of rubber, like the members 24, 25, 26 and 27, and has a suitable fabric or other backing 44 which is stitched or otherwise secured to the neck band 45 of the jacket 10, this neck band, as seen in Fig. 3, including a rearward portion 46 and front portions 47 and 48. Thus, when the person is in the water the member 43 will tend to assume a position against the lower part of the head of the wearer, and will thus act as a pillow to prevent the wearer's head from falling to the side, keeping the wearer's head and chin in a better position for postponing exhaustion as much as possible. The collar member 43 is preferably arranged so that when the garment is in position upon the wearer's body the ends 43' and 43'' will meet at the front of the wearer's neck, so that the member 43 practically surrounds the neck. 100

For still further support of the body in rough water, or for a long period, I preferably equip the jacket 10 with a pair of U-shaped air inflatable members 49 and 50, which are provided with fabric or other backing portions 51 and 52 secured to the body portions 11 and 14, and 12 and 15, respectively, above the arm holes 18 and 19 respectively, the members 49 and 50 thus surrounding the upper part of the wearer's arms just below the shoulders. The members 49 and 50, with thin attaching portions 51 and 52 respectively, thus constitute buoyant sleeve portions which have an appreciable effect in increasing the buoyancy of the garment and effectually supporting the wearer's 110 body in the water. 120

Considerable particularities of description, as to materials, part details, dimensions, capacities and utilities may have been herein indulged in, but it will be understood that

these statements, made with particular reference to the embodiments of the invention illustrated in the drawings, are not in any way to be taken as definitive or limitative of the invention. Inasmuch as many changes could be made in the above constructions, and many apparently widely different embodiments of the invention could be made without departing from the scope thereof, it is intended that all matter contained in the above description or shown in the accompanying drawings shall be interpreted as illustrative and not in a limiting sense.

It is also to be understood that the language contained in the following claims is intended to cover all the generic and specific features of the invention herein described, and all statements of the scope of the invention which, as a matter of language, might be said to fall therebetween.

In other words, the scope of protection contemplated is to be taken solely from the appended claims, interpreted as broadly as is consistent with the prior art.

What I claim is:

1. A life saving appliance comprising a jacket including a body encircling portion having a back and right and left hand front sections, a pair of air inflatable members secured to the inner side of said back, a pair of complementary air inflatable members secured one at the inner side of each of said front sections, a plurality of strap members depending from said jacket sections at the back, sides and front of the jacket, each of said straps having a loop at its lower end, a belt extending horizontally through the loops of said straps, and complementary fastening devices on said front sections.

2. A life saving appliance comprising a jacket including a body encircling portion having a back and right and left hand front sections, a pair of air inflatable members secured to the inner side of said back, a pair of complementary air inflatable members secured one at the inner side of each of said front sections, a plurality of strap members depending from said jacket sections at the back, sides and front of the jacket, each of said straps having a loop at its lower end, a belt extending horizontally through the loops of said straps, complementary fastening devices on said front sections, a U-shaped air inflatable tubular collar member secured to the neck of said jacket and adapted to encircle the neck of the wearer.

3. A life saving appliance comprising a jacket including a body encircling portion having a back and right and left hand front sections, a pair of reniform air inflatable

members secured to the inner side of said back, a pair of complementary reniform air inflatable members secured one at the inner side of each of said front sections, each of said reniform members including an elongated portion and a shorter portion of larger diameter, the elongated portions of each pair of said reniform members being adjacent to each other, with the larger diameter portions disposed in a substantially horizontal plane when the jacket is in position on the body, a plurality of strap members depending from said jacket sections at the back, sides and front of the jacket, each of said straps having a loop at its lower end, a belt extending horizontally through the loops of said straps, and complementary fastening devices on said front sections.

4. A life saving appliance comprising a jacket including a body encircling portion having a back and right and left hand front sections, a pair of reniform air inflatable members secured to the inner side of said back, a pair of complementary reniform air inflatable members secured one at the inner side of each of said front sections, each of said reniform members including an elongated portion and a shorter portion of larger diameter, the elongated portions of each pair of said reniform members being adjacent to each other, with the larger diameter portions disposed in a substantially horizontal plane when the jacket is in position on the body, a plurality of strap members depending from said jacket sections at the back, sides and front of the jacket, each of said straps having a loop at its lower end, a belt extending horizontally through the loops of said straps, complementary fastening devices on said front sections, and a U-shaped air inflatable tubular collar member secured to the neck of said jacket and adapted to encircle the neck of the wearer.

5. A life saving appliance comprising a jacket including a body encircling portion having a back and right and left hand front sections, a pair of reniform air inflatable members secured to the inner side of said back, a pair of complementary reniform air inflatable members secured one at the inner side of each of said front sections, each of said reniform members including an elongated portion and a shorter portion of larger diameter, the elongated portions of each pair of said reniform members being adjacent to each other, with the larger diameter portions disposed in a substantially horizontal plane when the jacket is in position on the body, a plurality of strap members depending from said jacket sections at the back, sides and front of the jacket, each of said straps having a loop at its lower end, a belt extending horizontally through the loops of said straps, complementary fastening devices on said front sections, and a pair of sleeve members

secured to said jacket, each of said sleeve members including a U-shaped air inflatable tubular member arranged to embrace the outer side of the arm below the shoulder of the wearer.

6. A life saving appliance comprising a jacket including a body encircling portion having a back and right and left hand front sections, a pair of reniform air inflatable members secured to the inner side of said back, a pair of complementary reniform air inflatable members secured one at the inner side of each of said front sections, each of said reniform members including an elongated portion and a shorter portion of larger diameter, the elongated portions of each pair of said reniform members being adjacent to each other, with the larger diameter portions disposed in a substantially horizontal plane when the jacket is in position on the body, a plurality of strap members depending from said jacket sections at the back, sides and front of the jacket, each of said straps having a loop at its lower end, a belt extending horizontally through the loops of said straps, complementary fastening devices on said front sections, a U-shaped air inflatable tubular collar member secured to the neck of said jacket and adapted to encircle the neck of the wearer, and a pair of sleeve members secured to said jacket, each of said sleeve members including a U-shaped air inflatable tubular member arranged to embrace the outer side of the arm below the shoulder of the wearer.

7. In testimony whereof I hereby affix my signature.

ISSIDORE WOSK.
